(57) **CLAIM**

The ornamental design for a curved surface building module, as shown and described.

DESCRIPTION

FIG. 1 is a perspective view from the front of a building module.

FIG. 2 is a perspective view from the right side of the building module.

FIG. 3 is a top view of the building module.

FIG. 4 is a bottom view of the building module.

FIG. 5 is a front elevation view of the building module. The back elevation view is the same.

FIG. 6 is a right side elevation view of the building module. The left side elevation is the same.

FIG. 7 is a corner elevation view from the front right corner of the building module; and,

FIG. 8 is a corner elevation view from the front left corner of the building module.

The broken lines are for illustrative purposes only and form no part of the claimed design.
